THE COLUMBIA PLANOGRAPH CO., WASHINGTON, D. C.

UNITED STATES PATENT OFFICE.

ROBERT C. McCaleb, OF MILWAUKEE, WISCONSIN.

RAZOR-SHARPENING MACHINE.

1,187,354.

Specification of Letters Patent. Patented June 13, 1916.

Application filed September 15, 1915. Serial No. 50,872.

To all whom it may concern:

Be it known that I, ROBERT C. McCaleb, a citizen of the United States, residing at Milwaukee, in the county of Milwaukee and State of Wisconsin, have invented a new and useful Razor-Sharpener Machine, of which the following is a specification.

The device forming the subject matter of this application is adapted to be employed for sharpening razor blades.

One object of the present invention is to provide novel means for actuating the blade holders, so that the blades in the blade holders may be made to coöperate properly with the sharpening elements.

Another object of the invention is to provide a device of this type in which the blade holders are mounted for reversible rocking movement, to permit the blade holders to coöperate with sharpening elements carried by the adjacent faces of a pair of disks, the disks and portions of the blade supporting means being provided with interengaging elements whereby reversible rocking movement may be imparted to the blade holders.

Another object of the invention is to provide novel means whereby the blade holder is mounted upon its support in such a manner as to accommodate blades of different widths, and to permit a blade in the holder to coact properly with the side face of the sharpening member.

It is within the scope of the invention to improve generally and to enhance the utility of devices of that type to which the present invention appertains.

With the above and other objects in view which will appear as the description proceeds, the invention resides in the combination and arrangement of parts and in the details of construction hereinafter described and claimed, it being understood that changes in the precise embodiment of the invention herein disclosed can be made within the scope of what is claimed without departing from the spirit of the invention.

In the accompanying drawings:—Figure 1 shows the invention in side elevation; Fig. 2 is a vertical transverse section whereby sundry parts appear in elevation; Fig. 3 is a plan disclosing one of the sharpening disks; Fig. 4 is a fragmental perspective showing one of the actuating members or cams which are carried by the sharpening disks; Fig. 5 is a fragmental sectional view

illustrating the means whereby the sharpening disks and other portions of the structure are mounted upon the drive shaft; Fig. 6 is a fragmental vertical section taken at right angles to the cutting plane in Fig. 2; Fig. 7 is a rear elevation of one of the actuating members or cams; Fig. 8 is a fragmental sectional view illustrating the means whereby the actuating members or cams are adjustably connected with the sharpening disks; Fig. 9 is a fragmental section showing a portion of the hub which receives the blade holding shafts; Fig. 10 is a perspective of one of the blade holding shafts; Fig. 11 is a transverse section of the element shown in Fig. 10; Fig. 12 is a sectional detail illustrating a modified form of blade holding means; Fig. 13 is a cross section on the line 13—13 of Fig. 12; Fig. 14 is a perspective delineating a modified form of blade holder.

In carrying out the invention there is provided a support embodying a pair of side frames denoted in Fig. 2 by the reference character 1. The side frames 1, embody as shown in Fig. 1, diverging legs 2 merging into a hub 3. Radiating from each hub 3 are arms 4 supporting an annular frame 5.

Comparing Figs. 5, 2 and 1, it will be observed that a drive shaft 6 is provided, the ends 7 of the drive shaft 6 being journaled for rotation in the hubs 3 of the supporting structure. Secured to the drive shaft 6 is a drive wheel 8 about which may be passed a belt 9, although if desired any other suitable means may be provided for rotating the drive shaft. In the drawings the drive shaft 6 is shown as squared at one end to receive a crank. Intermediate its ends, the drive shaft 8 is provided with a shoulder 11 against which abuts a disk 10, constituting a sharpening member, the disk 10 being provided with a hub 12 which encloses the drive shaft 6. Disposed in parallel relation to the disk 10 is a disk 14 provided with a hub 15, the hub 15 of the disk 14 and the hub 12 of the disk 10 being halved together as shown at 16 whereby the disks 10 and 14 are connected for simultaneous rotation. The drive shaft 6 is threaded adjacent one end as shown at 17, the threaded portion 17 of the drive shaft receiving a nut 18 which, bearing against the disk 14 holds the halved portions 16 of the hubs of the disks 14 and 10 together and

presses the disk 10 against the shoulder 11 on the drive shaft 8. Thus, both disks are operatively connected with the shaft 7 to rotate therewith when the latter is rotated by means of the drive wheel 8 or a crank and the belt 9 or their mechanical equivalents.

Applied to the adjacent faces of each of the disks 10 and 14 is an abrasive element 19 which may be a strip of leather or the like, each abrasive element 19 preferably being of semi-circular form, as Fig. 6 will most clearly show. Mounted upon the adjacent or inner faces of the disks 10 and 14 are actuating members 20 of curved form, the ends of the actuating members 20 being inclined as shown at 21, so that the actuating members in effect act as cams. As shown in Fig. 7, each actuating member or cam 20 is provided upon its inner face with a plurality of openings 22, adapted to receive, in threaded engagement, screws 23 journaled for rotation in the disks 10 or 14, reference being had to Fig. 8 for a clear understanding of the details last above outlined. The screws 23 are provided at their outer ends with heads 24 coacting with the outer faces of the disks 10 and 14. Compression springs surround the screws 23, the outer ends of the compression springs 25 bearing against the respective disks, and the inner ends of the compression springs bearing against the actuating members or cams 20, the latter elements if desired being recessed as shown at 26 in Fig. 8 to receive the inner ends of the compression springs 25.

Surrounding the interfitting hubs 15 and 12 of the sharpening disks is a support 27 preferably in the form of a hub embodying sleeves 27^a against which the disks 10 and 14 abut. The hub 27 is not secured to the hubs 15 and 12 of the sharpening disks. In its periphery, the hub or support 27 is notched as shown at 28 to define a plurality of shoulders 29 in which openings 30 are formed, the axes of the openings 30 being parallel to the side face of the hub 27. In this connection it is to be noted that, as indicated in Fig. 9, the openings 30 are not disposed radially with respect to the hub 27 but define acute angles with respect to the radii of the hub.

In the openings 30 of the hub 27 and in the fixed annular frame 5 are journaled for rocking movement, shafts 32, the bearing ends of which are denoted by the reference character 31. Each of the shafts 32 is provided with an eccentric portion 33, these eccentric portions 33 being adapted to coat with the disk-carried cams 20 in a manner which will be pointed out hereinafter. Secured to each shaft 32 is a blade holder 34 of arched form. A pivot element 35 unites each blade holder 34 with its shaft.

65 In practical operation, the sharpening

disks 10 and 14 are rotated by means of the drive shaft 6 and the drive wheel 8 or its equivalent. The hub 27 and the frame 5 remain fixed. When the disks 10 and 14 are rotated, the cams 20 thereon engage 70 with the eccentric portions 33 of the shafts 32 and impart a reversible rocking movement to the shafts, the blade holders on the shafts being brought successively into engagement with the abrasive elements 19 on 75 the disks by the action of the respective cams 20. In this manner, a group of blade holders 34 are first swung toward the abrasive element 19 on one disk and then toward the abrasive element on the other 80 disk, opposed sides of the blades in the holders thus being brought into engagement with the abrasive elements 19 on the respective disks.

Owing to the fact that each blade holder 35 34 is pivotally supported on the shaft 32 as shown at 35 in Fig. 10, the blade holder is permitted to tilt, so that the blade therein will coat properly with the abrasive element 19.

90 The pressure exerted by the cams 20 against the eccentric portions 33 of the shafts 32 and consequently the pressure exerted by the blades in the holders 34 against the abrasive elements 19 may be adjusted 95 by rotating the screws 23, thereby to vary the compressive effort of the springs 25.

It is to be observed, referring particularly to Fig. 6 that the blade holders 34 are not all disposed at the same distance 100 from the axis of rotation of the shaft 6, but are placed in spiral form with respect to the said axis. Consequently, all portions of the abrasive elements 19 are rendered effective, and the blades in the respective holders 105 are prevented from sweeping across the abrasive elements 19 in alinement.

Attention is directed to the fact that the shafts 32 and consequently the blade holders 34 are not disposed radially of the 110 disks 10 and 14. As a consequence, the abrasive element 19 when it coats with the blades in the blade holders 34 exerts a diagonal or angular sharpening action upon the blades as distinguished from a sharpening 115 action at right angles to the cutting edges of the blades.

In Fig. 12 of the drawings, a modified form of the invention is shown. The shaft 36 corresponds to the shaft 32. Applied to the shaft 36 and extended transversely thereof is an arched strip 37 provided with resilient ears 38 receiving pivotally the ends of bails 39 passing through ears 40 formed at the ends of a support 41 preferably taking the form of a bowed spring. An arched blade holder 41 is shown and by means of a pivot element 43, the blade holder 42 is mounted upon the spring 41 to swing thereon. A resilient tongue 44 is struck from 130

the strip 37 and extends through an opening 45 in the shaft 36. The tongue 44 bears upon the pivot element 43 or upon some accessible portion of the support 41. Owing 5 to the presence of the pivot element 43, the blade holder 42 is permitted to tilt so that the blade therein will coöperate properly with the abrasive elements on the sharpening disks. It is to be observed, further, that, 10 owing to the presence of the spring 41, the blade holder 42 is permitted to move toward and away from the shaft 36. In this manner, blades of different widths may be accommodated, the function of the spring 15 tongue 44 being to thrust the holder 42 outwardly so that the blade therein will coact with the abrasive elements on the disks.

When a thin blade is to be sharpened, the structure shown in Fig. 14 may be resorted 20 to. This modification embodies a pair of jaws 46 terminating in handles 47, the parts 46 and 47 of the respective parts of the holder being hingedly connected in any desired manner as shown at 50. The handles 25 47 may be provided with laterally extended finger pieces 48 facilitating the opening of the jaws 46. The jaws 46 adjacent their outer ends may be equipped with resilient facing strips 49 adapted to receive and hold 30 the blade which is to be sharpened. The blade holder shown in Fig. 14, when the constituent parts thereof are folded together, is adapted to be placed in the holder 34 of Fig. 10 or in the holder 42 of Fig. 12.

35 The cams 20 and the eccentric portions 33 of the shafts 32 may be described as interengaging elements which coact to produce a reversible rocking movement in the shafts 32.

40 Especial attention is directed to the fact that the machine herein disclosed permits a slow speed grinding of razor blades, thus preventing an overheating of the blades, owing to their thinness, the sharpening process, nevertheless, being carried out in a comparatively short space of time, owing to the large number of blades which are handled at once.

Having thus described the invention, 45 what is claimed is:—

1. In a device of the class described, a supporting structure embodying sides and an annular frame supported by the sides; a drive shaft journaled in the sides; spaced 55 sharpening members secured to the drive shaft; a hub located between the sharpening members, the shaft being rotatable in the hub; other shafts, the outer ends of which are journaled in the annular frame, the inner ends of which are journaled in the hub, the shafts comprising eccentric portions; blade holders carried by said other shafts; and cams upon the inner faces of the sharpening members, the cams being adapted to 60 coact with the eccentric portions of said other shafts to impart a reverse rocking movement thereto.
2. In a device of the class described, a supporting structure; spaced sharpening members journaled thereon; shafts mounted 70 for reversible rocking movement on the supporting structure between the sharpening members, and provided with eccentric portions; blade holders on the shafts and adapted to coact with the sharpening members when the shafts are rocked; cams adapted to coact with the eccentric portions of the shafts, the cams and the eccentric portions of the shaft constituting interengaging elements for imparting a reversible 75 rocking movement to the shafts; and means for yieldably connecting the cams with the sharpening members for movement toward and away from the sharpening members.
3. In a device of the class described, a 80 supporting structure; spaced sharpening members journaled thereon; shafts mounted on the supporting structure between the sharpening members for reversible rocking movement, the shafts being provided with eccentric portions; blade holders on the shafts and adapted to coact with the sharpening members when the shafts are rocked; cams coacting with the eccentric portions of the shafts, the cams and the eccentric portions of the shafts constituting interengaging 85 elements for imparting a reversible rocking movement to the shafts; and means for connecting the cams with the sharpening members adjustably, whereby the cams 90 sharpening members.
4. In a device of the class described, a supporting structure; spaced sharpening members thereon; shafts mounted for reversible rocking movement on the supporting structure between the sharpening members, the shafts being provided with eccentric portions; blade holders on the shafts and adapted to coact with the sharpening members when the shafts are rocked; cams 95 coacting with the eccentric portions of the shafts, the cams and the eccentric portions of the shafts constituting interengaging elements for imparting a reversible rocking movement to the shafts; and means for connecting the cams with the sharpening members adjustably, whereby the cams 100 sharpening members.
5. In a device of the class described, a supporting structure; spaced sharpening members journaled thereon; shafts mounted for reversible rocking movement on the supporting structure between the sharpening members; blade holders; means for pivotally connecting the blade holders with the 105 shafts, whereby the blade holders may tilt on the shafts transversely of the plane defined by the shafts, thereby to permit the blade holders to coact with the sharpening members; and interengaging elements on 110
6. In a device of the class described, a supporting structure; spaced sharpening members journaled thereon; shafts mounted for reversible rocking movement on the supporting structure between the sharpening members; blade holders; means for pivotally connecting the blade holders with the 115 shafts, whereby the blade holders may tilt on the shafts transversely of the plane defined by the shafts, thereby to permit the blade holders to coact with the sharpening members; and interengaging elements on 120
7. In a device of the class described, a supporting structure; spaced sharpening members journaled thereon; shafts mounted for reversible rocking movement on the supporting structure between the sharpening members; blade holders; means for pivotally connecting the blade holders with the 125 shafts, whereby the blade holders may tilt on the shafts transversely of the plane defined by the shafts, thereby to permit the blade holders to coact with the sharpening members; and interengaging elements on 130

the shafts and the sharpening members for imparting a reversible rocking movement to the shafts.

6. In a device of the class described, a supporting structure; spaced disks journaled on the supporting structure; abrasive members mounted on the adjacent side members of the disks; shafts mounted for reversible rocking movement on the supporting structure, and blade holders on the shafts, the blade holders being adapted to coact with the respective abrasive members when the rocking movement of the shafts is reversed, the shafts and the blade holders being disposed at acute angles to the radii of the disks; and interengaging elements on the shafts and on the disks for imparting a reversible rocking movement to the shafts.

7. In a device of the class described, a supporting structure; spaced disks journaled on the supporting structure; abrasive members mounted on the adjacent side faces of the disks; shafts mounted for reversible rocking movement on the supporting structure; and blade holders on the shafts, the blade holders being adapted to coact with the respective abrasive members when the rocking movement of the shafts is reversed, the blade holders being disposed on the several shafts in spiral form with respect to the center of rotation of the disks; and interengaging elements on the shafts and on the disks for imparting a reversible rocking movement to the shafts.

8. In a device of the class described, a supporting structure; spaced disks journaled on the supporting structure; abrasive members mounted on the adjacent side faces of the disks; shafts mounted for reversible rocking movement in the supporting structure; and blade holders on the shafts, the blade holders being adapted to coact with the respective abrasive members when the rocking movement of the shafts is reversed, the blade holders and the shafts being disposed at acute angles to the radii of the disks, the blade holders being mounted upon the several shafts in spiral form with respect to the center of rotation of the disks; and interengaging elements on the shafts and on the disks for imparting a reversible rocking movement to the shafts.

9. In a device of the class described, a supporting structure; spaced sharpening members journaled thereon; shafts mounted for reversible rocking movement on the supporting structure between the sharpening members; blade holders adapted to coact with the sharpening members when the

shafts are rocked; interengaging elements on the shafts and on the sharpening members for imparting a reversible rocking movement to the shafts; and means for connecting the blade holders with the shafts for bodily movement toward and away from the sharpening members, thereby to compensate for different widths of blades.

10. In a device of the class described, a supporting structure; spaced sharpening members journaled thereon; shafts mounted for reversible rocking movement on the supporting structure between the sharpening members; blade holders adapted to coact with the sharpening members when the shafts are rocked; interengaging elements on the shafts and the sharpening members for imparting a reversible rocking movement to the shafts; a support to which each blade holder is pivoted for swinging movement; and means for connecting each support with one shaft for movement toward and away from the sharpening members, thereby to accommodate blades of different widths.

11. In a device of the class described, co-operating mechanisms, one of which comprises a shaft, the other of which comprises a pair of sharpening disks between which the shaft is located; a supporting structure to which one of the said co-operating mechanisms is secured, the other of said co-operating mechanisms being mounted to move on the supporting structure with respect to the said fixed mechanism; a blade holder on the shaft, the shaft being mounted for reversible rocking movement, to permit the blade holder to co-operate with either disk; and interengaging elements on the disks and on said shaft for imparting a reversible rocking movement to the shaft.

12. In a device of the class described, a supporting structure; a disk carried by the supporting structure; a plurality of shafts connected with the supporting structure; means for producing relative rotary movement between the disk and the shafts; an abrasive member on the disk; and blade holders on the shafts and adapted to coact with the abrasive members, the blade holders being disposed in spiral form with respect to the center of the abrasive member.

In testimony that I claim the foregoing as my own, I have hereto affixed my signature in the presence of two witnesses.

ROBERT C. McCALEB.
